UNITED STATES PATENT OFFICE.

GEORGE W. THAYER, OF LAKE CITY, MINNESOTA.

ATTACHMENT FOR PORTABLE-ENGINE FURNACES.

SPECIFICATION forming part of Letters Patent No. 228,489, dated June 8, 1880.

Application filed April 7, 1880. (Model.)

To all whom it may concern:

Be it known that I, GEORGE W. THAYER, of Lake City, in the county of Wabashaw and State of Minnesota, have invented certain Improvements in Attachments to Farm or Portable Engine Boilers for Burning Straw as Fuel; and the invention consists in the construction of the device and its combination with such engine-boiler, as above cited.

10 In the drawings, Figure 1 represents a broken view of a furnace and boiler of a portable engine and my improvement attached thereto. Fig. 2 represents an upright sectional view of my device. Fig. 3 is a front view of the face-plate of a furnace and boiler of a portable or farm engine.

15 A represents the sheet-metal body of my device, having a projecting flange, *a*, to fit into the fuel-opening of a common portable-engine boiler, and another projecting flange, *a'*, to enter into the draft or cold-air opening into the ash-pit of the engine-boiler and through the openings *E* and *E'* of face-plate *D'* of the furnace *D*.

20 B is the receiving-chamber for the straw, which is forced therein through the opening closed by door *a''* into said chamber, where it is burned, the flame of the burning straw passing through the feed door or opening *E* into 25 the furnace *D*.

30 B' is the ash sink or box below the chamber *B*, and an inward projection, *b*, assists in holding the burning straw and in directing the flame and heat into the furnace *D* through the 35 opening *E*, and also directing the red-hot cinders of the partially-burned straw that fall into the ash-pit *B'*. By opening the door *b'*, a draft is formed by the admission of air from the outside through ash-pit *B'*, and through 40 the flanged opening *a'* in opening *E'* of the plate *D'*, thence under and through the grate of the furnace to the combustion-chamber, where the heat contained in this incandescent cinder is fully expended, thereby consuming 45 nearly all the ash of the straw or carrying it off with the products of combustion through the ordinary exit-flue.

The door *b'* in the ash-pit has a controlling-rod, *b''*, hinged to it, with eyes *b³* and *b⁴* there-

on that can be placed upon the projecting pin *a'''* at the rear end of the attachment *A*, so that the door may be held closed or open to admit the requisite amount of draft through the ash-pit.

50 F is a weight suspended in chamber *B* by rod *F'*, which rod extends above the jacket of chamber *B*, and has a knob, *f*, at its upper end and holes, *f'*, to receive a pin, *f''*, to hold the weight at the proper height while the chamber *B* is being charged with fresh straw.

55 *f³* is a supporting-bridge fixed upon jacket *A*, and when pin *f''* is in any of the holes *f'* the weight *F* is supported on the bridge *f³*, as seen in Fig. 2.

60 After chamber *B* is charged with fresh straw the pin *f''* is withdrawn from rod *F'*, and the full force of the weight bears upon the loose straw and compacts it, and thereby the straw is in better condition to be consumed, and as the straw is burned the weight settles down 65 upon the partially-consumed straw, which is in the condition of incandescent cinder, and when cold air is admitted through the door *b'* into the ash-pit in contact with such cinder in a pressed condition it acts to intensify the heat 70 thereof and to expend it to great advantage in contact with the boiler, thus increasing the heating capacity of the straw as fuel. This compacting the straw and cinder while burning is of great advantage when either high winds 75 or wet weather prevail, as it effects a more perfect combustion of the straw and cinder.

80 C represents wheels under the attachment *A*, having the ordinary axle *c*. *c' c'* are arms firmly secured to the under side of the attachment *A*, thence extending to the axle *c* of wheels *C*, where they are removably attached to said axle.

85 *d d* are strong eyes securely fixed to face-plate *D'* of furnace *D*. *d' d'* are hook-rods on either side of the removable and portable attachment *A*, and are secured to the axle *c* so as to be removable or not, as may be desired, and in such manner as to hinge on the axle, while they extend forward at the hook end to 90 be hooked into eyes *d* on the face-plate *D'*, and thereby hold the portable and detachable attachment in contact with the furnace *D* when-

ever the object is to burn straw, or its equivalent for fuel; but when other fuel, such as wood, is used in the furnace, then the hook-rods d' are released from the eyes d , and the device A can be removed from the engine upon the wheels C. Thus the attachment is a portable device whether attached to the engine or detached from it.

Having thus described my invention, what I claim is—

1. In a removable and portable attachment to a furnace, D, the sheet-metal device A, having the chamber B, weight E, ash-pit B', projection b, flanged openings a and a' , and doors a'' and b' , in combination with rods d' and eyes

d on face-plate D, as and for the purposes described.

2. In a removable attachment, A, to a portable-engine furnace, D, the ash-pit B', provided with air-supply door b' , arranged to pass the draft through opening E', under the boiler of the furnace, as and for the purposes described.

3. In combination with the attachment A of a portable-engine furnace having the receiving-chamber B and ash-pit B', the weight F, as and for the purpose described.

GEORGE W. THAYER.
